TRICYCLE OR THE LIKE

Ronald L. Reeves, 3920 Bowdoin,
Des Moines, Iowa 50313

Filed Apr. 14, 1966, Ser. No. 1,887

Term of patent 14 years

(Cl. D34—15)

FIGURE 1 is a side perspective view of a tricycle, showing my new design;

FIGURE 2 is a right side elevation view;

FIGURE 3 is a top view;

FIGURE 4 is a reduced bottom plan view;

FIGURE 5 is a front elevation view, and

FIGURE 6 is a rear elevation view.

The broken line portions shown in FIG. 1 have been omitted in FIGS. 2 through 6 for convenience of illustration.

The dominant features of my design reside in the portions shown in full lines, particularly in the combination of the over-sized steering wheel supported by the offset steering post and the rearwardly disposed seat, all as shown.

I claim:

The ornamental design for a tricycle or the like, substantially as shown and described.
